E. T. MARTIN,
HANGER FOR CONCRETE CEILINGS,
APPLICATION FILED AUG. 28, 1919.

1,351,112.

Patented Aug. 31, 1920.

UNITED STATES PATENT OFFICE.

EUGENE T. MARTIN, OF CHICAGO, ILLINOIS.

HANGER FOR CONCRETE CEILINGS.

1,351,112.

Specification of Letters Patent. Patented Aug. 31, 1920.

Application filed August 28, 1919. Serial No. 320,343.

To all whom it may concern:

Be it known that I, EUGENE T. MARTIN, a citizen of the United States, residing at Chicago, in the county of Cook and State 5 of Illinois, have invented certain new and useful Improvements in Hangers for Concrete Ceilings; and I do hereby declare the following to be a full, clear, and exact description of the invention, such as will enable others skilled in the art to which it 10 pertains to make and use the same.

This invention has for its object to provide a hanger for concrete ceilings, constituting more particularly a bolt socket adapted to be embedded in the concrete ceiling for subsequently suspending shafting-hangers and motors and the like from such ceiling.

The main object of the present invention 20 is to provide a hanger of the character defined, which is adapted to receive a bolt the lower end of which rests upon the bottom of the mold of the ceiling at the time of pouring the same and which, when the mold is 25 removed, will of its own weight project from the lower end of the socket of the hanger so that the location of the hangers can be plainly discerned after the ceiling has been plastered.

30 A further object of the invention is to provide a device of the character defined, wherein sufficient weight is imparted to the bolt to cause the same to readily project itself by gravity through a coating of fresh plaster applied to the ceiling after the mold thereof has been removed if the plasterer should unintentionally push the bolt up within the socket when applying the plaster.

Another object of the invention is to provide 40 a hanger of the character defined, wherein the bolt is very firmly and rigidly held in position for use without, however, constituting any parts of the device of such exact dimensions as would render them inoperative or difficult of operation in the 45 event of rust or corrosion of contacting surfaces and which will not require any machine finishing.

Other objects of the invention will be understood 50 from the following specification:

The invention consists of the features of construction and combinations of parts hereinafter fully described and particularly claimed:

55 In the accompanying drawings, illustrating suitable embodiment of the invention,

Figure 1 is an end elevation of a hanger socket constructed in accordance with the invention, showing the same embedded in a concrete ceiling.

60

Fig. 2 is a central longitudinal section on the line 2—2 of Fig. 1, the bottom of the mold for the ceiling being indicated.

65

Fig. 3 is an inverted plan view of the hanger.

65

Fig. 4 is a horizontal section of the same on line 4—4 of Fig. 2.

Fig. 5 is a detail perspective view of the block constituting a part of the device.

Fig. 6 is a sectional view of an interlocking 70 form of cover;

Fig. 7 is a perspective view of another form of interlocking cover.

The said hanger comprises a socket "A" 75 preferably made of cast iron or the like, which is rectangular in horizontal section and has parallel side walls and tapering end walls, the latter converging toward the bottom of the socket. In the bottom of the latter, centrally thereof, *i. e.*, equidistant 80 from the corners, is an opening "B" through which the shank of the bolt "C" is adapted to project, said opening being of somewhat larger diameter than that of the bolt for reasons which will be hereinafter more fully 85 pointed out.

Within the socket there is disposed a block "D" of cast iron having parallel side faces and tapering end faces, the taper of the latter being substantially coincident with 90 that of the end walls of the socket. The width of the block between its parallel side faces is substantially equal to the inner width of the socket between the side walls thereof.

All four of the faces of the block 95 "D" are provided with longitudinal grooves "E" which serve to render the same somewhat lighter and will cause the same to be more readily and snugly fitted into the socket "A." Said block "D" is reciprocable 100 in the socket from the upper end thereof to that point near the lower end thereof at which the tapering end walls thereof firmly engage the tapering end walls of the socket, the two positions being shown in full and 105 dotted lines, respectively, in Fig. 2. The said block "D" is provided with a central threaded opening which may extend partially or entirely through the same to receive the threaded upper end portion of the 110 bolt "C" of which it may be said to constitute the head.

Extending outwardly from the parallel side walls of the socket "A" are two flanges "F" each of which is provided with a perforation for the passage of a nail by means of which the socket is secured to the mold to hold it firmly in position while casting the ceiling.

The end walls of the socket "A" are provided at their upper end portions with parallel surfaces "G" which coact with the similar parallel surfaces of the side walls to provide a rectangular surface adapted to be engaged by the peripheral flange "H" of a cover "J" which is adapted to be mounted upon the socket "A" as the latter is mounted on the mold for the purpose of excluding water and cement from the socket, said cover being preferably composed of a light sheet metal.

Bordering the lower edge of the parallel faces "G" of the end walls are two outwardly extending ribs or projections "K" which serve to engage in the concrete for more firmly holding the socket in place therein.

The block "D" being relatively heavy and adding its weight to the bolt "C" will obviously cause the latter to fall by gravity to project the bolt "C" from the socket when the mold is removed and it is heavy enough to force its way by gravity through an ordinary layer of plaster applied to the ceiling after the mold is removed, should it occur that the plasterer lifts the bolt up into the socket when applying the plaster.

In order to prevent the possibility of little particles of plaster, which may find their way between the bolt "C" and the inner face of the opening "B" from preventing the fall by gravity of the bolt through and to penetrate the layer of plaster, the opening "B" is made relatively large in diameter. It is also made large for the purpose of permitting the shank of the bolt "C" to be slightly flexed to extend truly in the desired direction from the ceiling, it being obvious that molds for such structures are not apt to be absolutely accurate as to level of all surfaces. By allowing play in the opening "B" the bolt "C" may be positioned as desired when suspending hangers, motors and the like from the ceiling. The bolt "C" and block "D" are of a combined length equal to the total length of the socket "A" so that when the latter is positioned in the mold, said bolt will be completely housed in the socket without, however, interfering with the cover "J" thereof and being as a whole as long as the socket it cannot be retained in the socket against the action of gravity.

After the mold is removed and the bolt "C" moved downwardly to its normal position, the block "D" will become wedged very firmly in place in the socket "A," thus preventing lost motion relatively to the latter

and causing the bolt to be properly positioned independently of the opening "B." The bolt may be renewed whenever desired and obviously it can be replaced by a longer bolt or by any suitable hanging device for specified purposes such as pipe hangers or eye-bolts.

The device may also be employed advantageously in vertical walls. When so used a light helical compression spring "L" will be introduced between the block "D" and the cover "J" and means such as a wire or sheet metal yoke "M" used to hold the cover in place against the action of the spring. In place of the yoke "M" the cover may consist of a U-shaped strip "N" of sheet metal having its end flanges "O" channeled as at "P" to receive the end flanges "K" of the housing and which is adapted to be slid into place from one side of said housing.

The total length of the movable device is such that the lower end of the bolt cannot rise high enough within the socket to rest upon the upper surface of the bottom wall of the socket and thus be retained therein. In the form shown some of this length is made up by the spring "L," but it is obvious that when the spring is not used the bolt itself can be long enough to prevent it disappearing within the socket. This is to insure the dropping down of the bolt immediately the form is removed.

While I have shown the preferred embodiment of the invention in the accompanying drawing, it will be understood, of course, that such embodiment may be changed and varied in details of construction as mechanical skill and the needs of any particular installation may require without departing from the invention as defined in the appended claims.

I claim as my invention:

1. In a device of the kind described, a socket adapted to be embedded in concrete, one wall thereof flush with an outer face of the concrete, the socket having a space within same extending away from the face of the concrete, a block movable in said space from and toward said face, means preventing the removal of the block from the socket, a bolt having threaded engagement with the block, the overall length of the block and bolt being substantially the depth of said space from said face to permit the bolt to be pushed within the space and have its outer end rest in contact with the form against which said face of the concrete is to be formed.

2. In a device of the kind described, a socket to be embedded in concrete with one wall flush with an outer face of the concrete, means for retaining the socket against removal from the concrete, the socket being closed by a wall at its outer end provided with a bolt hole, a bolt extending through

said hole into the socket, a block held in the socket against rotation and movable in the socket from and toward the face of the concrete, the combined length of the bolt and 5 the block being substantially the depth of the socket from the face of the concrete, permitting the bolt to be lifted into the socket with its free end adapted to rest on the mold upon which the concrete is to be formed, the 10 bolt being free to drop by gravity with its free end extending beyond the face of the concrete when the mold is removed.

3. In a device of the kind described, a socket adapted to be embedded in concrete, 15 and having a wall adapted to be flush with an outer face of the concrete, said wall having a perforation through which a bolt can be inserted into the socket, a threaded member in the socket, means for preventing the 20 rotation of said member, said member being free to be moved from and toward said perforated wall of the socket, a bolt for engagement in said threaded opening, the bolt and block being adapted to be lifted up so 25 that the free end of the bolt will rest on the mold upon which the concrete is to be formed, and being adapted to drop freely when the mold is removed, the perforated wall preventing the removal of the threaded 30 member from the socket.

4. In a device of the kind described, a socket adapted to be embedded in concrete and having a wall adapted to be flush with an outer face of the concrete, said wall hav-

ing a perforation through which a bolt can 35 be inserted into the socket, a member within the socket provided with a threaded opening for receiving a bolt, the socket member having inclined walls which are closer together at their lower ends than at their upper ends and the coöperating walls of the threaded member being correspondingly inclined, the member being of such dimension that it wedgingly engages the inclined walls of the socket before it contacts with the perforated wall thereof, the total length of the bolt and the threaded member being substantially the length of the socket from the 40 face of the concrete, whereby the bolt can be lifted into the socket with its free end in 50 contact with the mold upon which the concrete is to be formed, said bolt and member being adapted to drop by gravity to project the bolt from the socket when the mold is removed.

5. In a device of the character described, an open topped socket having a wall adapted to be placed flush with a face of the concrete, said wall having an opening through which a bolt can project from the interior 60 of the socket, an interlocking cover for the top of the socket, said socket adapted to contain a non-rotatable nut to receive the bolt and deep enough to permit the bolt to be pushed into the socket until the outer 65 end of the bolt is flush with the outer face of said wall.

EUGENE T. MARTIN.
